UNITED STATES PATENT OFFICE

172,315

SHOE OR SIMILAR ARTICLE

Jacob Sandler, New York, N. Y.

Application May 18, 1953, Serial No. 25,037

Term of patent 7 years

(Cl. D7—7)

To all whom it may concern:

Be it known that I, Jacob Sandler, a citizen of the United States of America, residing in New York city, county of New York, and State of New York, have invented a new, original, and ornamental Design for a Shoe or Similar Article, of which the following is a specification, reference being had to the accompanying drawing, forming part thereof,

Fig. 1 is a plan view of a shoe or similar article, showing my new design.

Fig. 2 is a side elevation view.

I claim:

The ornamental design for a shoe or similar article, substantially as shown.
